CLAIM

I claim the ornamental design for a charging case for earbuds, as shown and described.

DESCRIPTION

The patent or application file contains at least one drawing executed in color. Copies of this patent or patent application publication with color drawing(s) will be provided by the Office upon request and payment of the necessary fee.

FIG. 1 is a top perspective view of a charging case for earbuds in accordance with an embodiment of the invention.

FIG. 2 is a top view of the charging case of FIG. 1.

FIG. 3 is a bottom view of the charging case of FIG. 1.

FIG. 4 is a front view of the charging case of FIG. 1.

FIG. 5 is a rear view of the charging case of FIG. 1.

FIG. 6 is a right-side view of the charging case of FIG. 1.

FIG. 7 is a left-side view of the charging case of FIG. 1.

FIG. 8 is a top perspective view of a charging case for earbuds in accordance with another embodiment of the invention.

FIG. 9 is a top view of the charging case of FIG. 8.

FIG. 10 is a bottom view of the charging case of FIG. 8.

FIG. 11 is a front view of the charging case of FIG. 8.

FIG. 12 is a rear view of the charging case of FIG. 8.

FIG. 13 is a right-side view of the charging case of FIG. 8; and,

FIG. 14 is a left-side view of the charging case of FIG. 8.
